UNITED STATES PATENT OFFICE.

EMILE BRONNERT, OF MÜLHAUSEN, ALSACE-LORRAINE, FRANCE.

PROCESS OF RECOVERING SALTS FORMED IN THE MANUFACTURE OF ARTIFICIAL SILK.

1,376,671.

Specification of Letters Patent.

Patented May 3, 1921.

No Drawing.

Application filed September 7, 1920. Serial No. 408,690.

To all whom it may concern:

Be it known that I, EMILE BRONNERT, a citizen of the Republic of France, residing at 1 Quai du Barrage, in Mülhausen, Alsace-
5 Lorraine, France, have invented certain new and useful Improvements in Processes of Recovering Salts Formed in the Manufacture of Artificial Silk, of which the following is a specification.

10 This invention relates to the production of artificial silk and its object is to provide a process for the suitable recovery of a spinning bath from the salts formed by the spinning of viscose in sulfuric acid mixed with
15 soluble sulfates.

It has already been proposed to recover the Glauber salt or sulfate of soda from the sulfuric acid baths used with admixture of salt for spinning viscose. Practically this
20 recovery has not yet been carried out in any artificial silk factory of the world, at least not to any considerable or useful extent; on the contrary the washing water containing the Glauber salt has all been allowed to run
25 to waste and so far not utilized.

Recently, however, on again taking up the wholesale production of the special line of artificial silk known as "staple fiber," the idea was again entertained of the utilization
30 of the salts contained in the spinning baths, and a practical solution of the problem was sought.

New it has been found that from the spinning baths properly so-called the sodium sulfate formed is recoverable with difficulty. For example, in spinning baths of strong salt content and the usual content of sulfuric acid exceeding the bisulfate proportion, almost the whole quantity of sodium
35 sulfate formed remains adherent to the threads arising from the bath with the usual speed of about 45 m. per minute.

A portion of the salt may undoubtedly be recovered by allowing its solution to drip off the spools or reels or by shaking it off the threads. The major portion, however, can only be recovered by subsequent lixiviation of the threads and the diluted wash water must then be steamed with the expenditure
45 of coal and then caused to crystallize, sometimes by additional cooling. The salt thus crystallized out must then be removed and be separated from the acid mother lye by lixiviation.

50 The free acid still present in the wash

water can be neutralized by the addition of caustic soda or soda, so as to permit ordinary pans of iron or silicon iron to be used.

Then attempts were made to reduce the quantity of wash water by lixiviation of the raw, slightly acid thread masses with limited quantities of water and by repeated washing with the same water. On using baths of strong salt content it was found that, upon the addition of 3 liters of water per hour, or
60 the first wash water upon the masses of thread (about 3 kg. dry weight) a further enrichment is no longer possible after the wash water has been once used owing to the occurrence of a compensatory condition of
65 about 18 to 20% sodium sulfate and 3-4% acid in the wash water and upon the thread. In cold weather the tendency for crystallization of the Glauber salt is also manifest in an unpleasant manner, namely by stopping
70 up of the pipes. Finally care must be taken not to begin too soon with the use of the fresh threads as otherwise prior to the complete coagulation and neutralization of the
75 soda the threads only stick or adhere together.

Now it has been found that there can be recovered from the thread masses a far greater quantity of salt if, at the beginning, not pure water but diluted sulfuric acid is
80 used for the lixiviation, the content of the solution in acid being sufficient to change the sulfate contained in the threads into the much more easily soluble bisulfate. This does not choke the pipes. A 10 to 12% acid
85 is preferable, but I am not bound to this concentration. The concentration must be adapted to the bath concentrations used at the time.

The greatest advantage, however, consists
90 in the fact that the working up of these concentrated solutions is extremely simple and advantageous.

Consideration of the matter will show that it would be quite contrary to the purpose
100 in view to attempt to produce Glauber salt, either for sale or for reuse in the spinning bath by dissolving the Glauber salt in sulfuric acid. To render the Glauber salt in condition for sale a further purification
105 would be necessary either by crystallizing or by filtration of the solutions for the removal of adherent quantities of sulfur from the spinning bath.

110 A quantity of fresh sulfuric acid must

always be supplied to the existing bath, in the same proportion as this is weakened by the caustic soda from the viscose and furthermore sulfate as a substitute for that carried away must be added; thus the production of bisulfate or of a concentrated bisulfate solution, even also containing excess acid under certain circumstances, is the most suitable method of recuperation of the sodium sulfate formed upon the threads.

The corresponding sulfuric acid washing waters are concentrated in suitable manner, as, for example, in steam heated lead pans, in sulfuric acid concentrating towers, where-
15 in hot gases of combustion meet the trickling bisulfate solution, or by means of other devices, in a state to be directly run back to the spinning bath, and used therein without other alteration of its concentration, as the
20 concentrating in the concentration apparatus may be carried out so as to reduce the strength to the normal or standard used in the baths, or within permissible approximations of such standards.
25 The lixiviation of the thread masses and liberation as far as possible from the washing liquid can be effected according to the most varied processes, either in vats with circulating liquors and subsequent pressing
30 or squeezing or upon the receiving devices themselves and subsequent squeezing or the like after draining off and removal or by means of any other process.

Recently owing to failing supplies of caustic soda, caustic potash has been used for the production of viscose. The sulfate of

potash arising possesses still more than Glauber salt the unpleasant property of crystallizing. Hence when working with potash combinations the use of the process described is preëminently useful as potassium bisulfate is just as easily soluble. Because of the high commercial value of potash, the reduction in the potash losses is of considerable importance.

Magnesium and zinc salts, which often serve as an addition to spinning baths, do not effect my process for the recovery of the salts formed.

What I claim is:

1. The process of recovering the salts formed in the manufacture of artificial silk consisting in lixiviating the threads with dilute sulfuric acid to convert the salts formed in the spinning bath into salts of a more soluble character.

2. The process of recovering salts formed in sulfuric acid precipitation baths containing dissolved sulfates used in the manufacture of artificial silk from viscose solutions, comprising lixiviating the threads in sulfuric acid solution to convert the sulfates formed in the precipitating bath into the bisulfate.

In witness whereof I have hereunto signed my name in the presence of two subscribing witnesses.

EMILE BRONNERT.
